UNITED STATES PATENT OFFICE.

GEORGE GLAUDEL, OF LOS ANGELES, CALIFORNIA.

AUTOMOBILE-CURTAIN.

1,305,460.

Specification of Letters Patent. Patented June 3, 1919.

Application filed January 6, 1919. Serial No. 269,810.

To all whom it may concern:

Be it known that I, GEORGE GLAUDEL, a citizen of France, residing at 1368 Wall St., Los Angeles, in the county of Los Angeles and State of California, have invented new and useful Improvements in Automobile-Curtains, of which the following is a specification.

My object is to make an improved automobile curtain window, and my invention consists of the novel features herein shown, described and claimed.

The principal object of my invention is to make a curtain window frame filling all of the requirements, and at the same time provide means whereby the frame is easily applied to the curtain.

Figure 1 is a fragmentary outside elevation of an automobile curtain having a window embodying the principles of my invention, the view being taken looking in the direction indicated by the arrow 1 in Fig. 2.

Fig. 2 is a sectional detail diametrically through the window as on the line 2—2 of Fig. 1.

Fig. 3 is a fragmentary enlarged sectional detail as on the line 3—3 of Fig. 1.

Fig. 4 is a fragmentary perspective of the interlocking parts shown in section in Fig. 3.

The inner window frame member 1 is an annular ring built up of wood. The ring 1 has a flat inner face 2 and notches 3 extending outwardly from the face 2. From the flat face 2 the inner side face 4 is comparatively smooth and slightly curved, and the outer side face 5 is flat to a point beyond the notches 3, and then the outer side face has a slight bulge 6 extending outwardly and a curved face 7 joining at the periphery 8 with the curved inner side face 4. Spring casings 9 are formed by boring holes from the curved inner side face 4, and expansive coil springs 10 are placed in these spring casings. Leaf springs 11 are placed against the curved inner faces 4 and against the leaf springs 9. The outer ends of the springs are held in place by screws 12 inserted through the metal and screwed into the wood near the periphery 8. The inner free ends 13 of the springs extend inwardly from the bodies of the springs at approximately right angles and in the notches 3, there being hooks 14 at the ends of the springs, said hooks 14 being substantially at the transverse center of the ring 1.

The outer window frame 15 is an annular

metal ring having a flat inner face 16 and a curved outer face 17, so that the ring is substantially half round in cross section. Tongues 18 project from the flat face 16 in 60 positions to fit in the notches 3, and teeth 19 extend from the outer faces of the tongues to interlock with the hooks 14. The extreme ends 20 of the tongues 18 are chisel shaped, thereby forming inclined guide faces 21 65 over which the hooks 14 will pass before they snap into engagement with the teeth 19.

When it is desired to apply my window frame to an automobile curtain or top 22, the ring 1 is placed against the inner face of the 70 outer material 23. A penknife, or the like, is placed in the notches 3 and pushed through the material 23; then the ring 15 is placed against the outer side of the material and the tongues 18 press through the slits 75 formed by the penknife, and as the tongues pass through the material into the notches 3 the hooks 14 will pass along the inclined faces 21 and snap into engagement with the teeth 19, thereby firmly securing the material 80 23 between the ring 1 and the ring 15, the flat face 16 of the ring 15 pressing against the outer face of the material and pressing the material against the face 5 of the ring 1.

It is desirable that the parts be so located 85 that the material will be firmly gripped between the two rings. Then a sharp knife is employed to cut the material 23 at the inner edge of the ring 15 all the way around, thereby making the window opening bounded by the edge 24 of the material 23. Then the lining 25 is prepared with an opening corresponding substantially to the window opening, and the lining is placed against the inner face of the ring 1 with its edge 26 around 90 the opening drawn over against the face 2 of the ring. Then the window glass 27 is placed in position from the inside of the curtain, so that the edge of the glass will press outwardly against the material 23 outside of the edge 24 and inside of the face 2, thereby making a non-metallic cushion for supporting the glass against the ring 15, and the edge 26 extends around the periphery of 95 the glass, and a non-metallic binding 28 is placed against the inner face of the edge of the glass and secured in place by tacks 29 driven through the material into the ring 1. The binding 28 is formed by folding a piece of top material to form the finished inner 100 edge 30, and the raw edges of the material are placed against the glass, thereby forming 105 110

ing a non-metallic backing for the glass in opposition to the non-metallic cushion formed by the material 23.

The leading feature of this construction 5 is the snap connection between the ring 1 and the ring 15, and the leading advantage of this construction is due to the ease with which it may be securely applied.

Various changes may be made without departing from the spirit of my invention as 10 claimed.

I claim:

1. In an automobile curtain window frame, an inner ring of wood having 15 notches, spring hooks extending into the notches, and an outer metallic ring having tongues extending into the notches and adapted to be engaged by the spring hooks.
2. In an automobile curtain window con-

struction, an inner wooden ring having 20 notches extending from its inner face; spring hooks secured to the ring and extending into the notches; a fabric fitting against the outer face of the ring; an outer metallic ring having tongues adapted to be pushed 25 through the fabric into the notches and into engagement with the spring hooks, thereby clamping the material between the inner and outer rings; a lining fitting against the inner face of the inner ring and extending through 30 the opening in the ring against the first material; a window glass inserted from the inside and fitting against the first material and against the second material; and means for holding the glass against the outer ring. 35

In testimony whereof I have signed my name to this specification.

GEORGE GLAUDEL.
